US00D874911S

(12) **United States Design Patent** (10) Patent No.: **US D874,911 S**
(45) Date of Patent: **** Feb. 11, 2020**

(54) **FITTING**

- (71) Applicant: **Ergonomic Solutions International Limited**, Epsom (GB)
- (72) Inventor: **Benny Burmester**, Aalborg (DK)
- (73) Assignee: **ERGONOMIC SOLUTIONS INTERNATIONAL LIMITED**, Epsom (GB)
- (**) Term: **15 Years**
- (21) Appl. No.: **29/641,611**
- (22) Filed: **Mar. 23, 2018**

Related U.S. Application Data

- (63) Continuation of application No. 35/504,400, filed on Jan. 4, 2018 (U.S. filing date under 35 U.S.C. 384), and having an international filing date of Jan. 4, 2018.

Foreign Application Priority Data
